UNITED STATES PATENT OFFICE.

CHARLES PHILIPP EHMANN, OF MANCHESTER, ENGLAND.

BUNSEN TUBE FOR INCANDESCENT LIGHT, HEATING, OR COOKING APPARATUS.

SPECIFICATION forming part of Letters Patent No. 729,298, dated May 26, 1903.

Application filed October 7, 1901. Serial No. 77,887. (No model.)

To all whom it may concern:

Be it known that I, CHARLES PHILIPP EHMANN, merchant, a subject of the King of Great Britain, and a resident of 43 Blackfriars street, Manchester, England, have invented certain new and useful Improvements in Bunsen Tubes for Incandescent Light, Heating, or Cooking Apparatus, of which the following is a specification.

10 In the hitherto known and employed Bunsen tubes for incandescent burners and cooking apparatus the gas entering from the nozzle flows freely through the Bunsen tube and draws on its way atmospheric air. The mixture of gas and air is here insufficient, and thus the combustion imperfect.

The present invention has for its object, therefore, various improvements in such Bunsen burners, immaterial as to what purpose 20 the same serve, the essential feature of the invention consisting in inserting within the Bunsen tube a resistance by means of which in the gas and air current various whirls or spiral paths are produced, whereby an intense 25 and thorough mixing of the gas and air, and thus a complete combustion of the gas mixture, is attained. The complete combustion is, furthermore, supported by the beforementioned inserted resistance in the Bunsen tube, 30 as the same consists of a good heat-conducting material, so that it becomes intensely hot and effects a preliminary warming of the gas mixture.

In the accompanying drawings some constructions for carrying the invention into effect are shown, in which—

Figure 1 illustrates the employment of the improved device for incandescent-light burners, the view showing a longitudinal section 40 through the burner. Fig. 2 represents a Bunsen tube for cooking or heating purposes in longitudinal section, in which a resistance corresponding to that of Fig. 1 is inserted.

Referring to Fig. 1, in the Bunsen tube *c* upon the gas-nozzle *b* a coiled spiral wire consisting, preferably, of copper is so inserted as to rest or bear upon the said nozzle *b*. The gas coming out of the latter, as well as the air introduced through the holes *f*, strikes 45 against the resistance *d* and receives the be-

forementioned whirl or spiral path which causes a thorough mixing of the gas and air. The prepared gas mixture passes then in known manner through the burner-crown *g* of the burner *a* to the outside of the burner, 55 where the same is completely ignited and consumed. In consequence of the combustion, however, both the burner *a* and thus, also, the wire spiral *d* become heated at the same time and give up their heat to the gas 60 mixture flowing through same, and thus warm the latter.

For the burners of heating and cooking apparatus, Fig. 2, the screw-shaped coiled wire *d*, serving as the resistance, is employed, the 65 same being inserted in the Bunsen tube *c* and placed upon the nozzle in exactly the same manner as described in reference to the incandescent gas-burner of Fig. 1. Also in this construction by means of the heated burner-crown *g* the copper wire *d* becomes heated, and consequently, also, the gas mixture heated 70 or warmed.

When employing this device for cooking and heating apparatus, the further advantage 75 is attained that in consequence of the complete combustion of the gas mixture the formation of badly-smelling vapors is avoided and the providing of special tubes to carry away such vapors thus rendered unnecessary. 80

Having thus described my invention, the following is what I claim as new therein and desire to secure by Letters Patent:

The combination with the burner-tube having an enlarged chamber at one end, said 85 chamber being provided with air-holes, and a gas-nozzle extending into said enlarged chamber, of a resistance comprising an immovable spirally-wound metallic wire seated upon the gas-nozzle, extending the full length 90 of said tube and impinging the walls of the narrowest portion of said tube to receive heat therefrom.

In witness whereof I have hereunto set my hand in presence of two witnesses.

CHARLES PHILIPP EHMANN.
